UNITED STATES PATENT OFFICE.

LOUIS ARONOWITZ, OF NEW YORK, N. Y.

CONSTRUCTION OF CEILINGS.

SPECIFICATION forming part of Letters Patent No. 600,704, dated March 15, 1898.

Application filed August 27, 1897. Serial No. 649,704. (No model.)

To all whom it may concern:

Be it known that I, LOUIS ARONOWITZ, of New York city, in the county and State of New York, have invented a new and useful Improvement in the Construction of Ceilings, of which the following is a full, clear, and exact description.

My invention relates to an improvement in the construction of ceilings; and it consists in a panel formed of bars and connecting-links in such a manner that it may be folded for transportation and inserted between the flanges of the ordinary floor-beams, being at the same time expanded into its normal shape.

Reference is to be had to the accompanying drawings, forming a part of this specification, in which similar characters of reference indicate corresponding parts in all the views.

Figure 1 is a plan view of a section or panel, showing my improved construction. Fig. 2 is a plan view of a section or panel folded. Figs. 3, 4, and 5 are end elevations of a portion of such panel, showing slightly different constructions.

The object of my invention is to construct the panels immediately supporting the ceiling in such a manner that the bars forming the same may be folded for transportation and expanded when put in place, thus obviating handwork at the building. In constructing these panels the bars B, formed, as shown in Fig. 3, of T-beams, or the bars B', as shown in Fig. 5, of two channel-irons placed back to back, are used to support the material of the ceiling. These bars are connected to each other by short links C, which are pivoted to the flanges of the bars and extend from one bar to the next adjacent bar. The bars are placed at such a distance apart from each other when in their expanded position as to receive a brick or tile placed between them and supported upon the lower flange of the bar. The bricks used for this purpose are shown in dotted lines in the drawings and are indicated by the letter D. The ordinary floor-beams are indicated by the letter A. The cross-bars B, forming the panel, are made of such a length as to fit snugly between the webs of the I-beams A.

In Fig. 2 the bars B are represented as folded

upon each other for transportation. When put in place in the building, the bars will be inserted between the parallel beams A and expanded into the position shown in Fig. 1. The bricks or tiles are then placed between the vertical webs of the bars and resting upon their bottom flanges. To the bottom of the panel lathing or any other suitable means for holding the plastering may be attached. In using this construction the panels may be quickly put in place and also quickly filled with fireproofing material—such as bricks, tiles, &c.

In Fig. 5 the bars are shown as made of channel-irons placed back to back, thus providing horizontal flanges at the top and bottom of the bars. With such a construction the bricks or tiles would be placed between the top and bottom flanges of the bars, as shown in Fig. 5.

The panels may be put together at a shop in sections of considerable length and then folded so that they may be readily transported. This enables the handwork to be done where especial facilities may be used for assembling the parts, leaving little handwork to be done at the building, which results in a considerable saving in the cost of the construction. The parts are all securely fastened together, each supporting the other, and making, consequently, a strong and rigid structure. This construction may also be used in the construction of floors—filling the space between large floor-beams. In such cases it may be desirable at times to place a layer of concrete or similar material over the bricks or tiles. My invention, however, pertains to the construction of the panel, consisting of bars B and connecting-links C, and the method of using the same with the floor-beams A.

As shown in Figs. 1 and 3, the links C are placed upon the upper surfaces of the flanges of the bars B. As shown in Fig. 4, these links are pivoted upon the under surfaces of the said flanges. Either position may be adopted.

Having thus described my invention, I claim as new and desire to secure by Letters Patent—

1. A ceiling-supporting panel, consisting of a series of bars flanged at their lower edge,

each bar being connected to the adjacent bars by pivoted links, substantially as described.

2. A ceiling-supporting panel consisting of a series of flanged bars of a length to fit between the webs of the adjacent floor or ceiling beams, and links connecting adjacent bars by pivots passing through the ends of

the links and the flanges of the flanged bars, substantially as described.

LOUIS ARONOWITZ.
